UNITED STATES PATENT OFFICE.

EDWARD S. JUDKINS, OF EAST PROVIDENCE, RHODE ISLAND.

CARRIER FOR BRAIDING-MACHINES.

1,258,781.

Specification of Letters Patent. Patented Mar. 12, 1918.

Application filed February 5, 1917. Serial No. 146,550.

To all whom it may concern:

Be it known that I, EDWARD S. JUDKINS, a citizen of the United States, and resident of the town of East Providence, in the county of Providence and State of Rhode Island, have invented certain new and useful Improvements in Carriers for Braiding-Machines, of which the following is a specification.

10 This invention relates to spool carriers for braiding machines, and has for its object to provide means in the carrier permitting the running speed to be increased over the ordinary style of carrier, said means including essentially a flexible, yieldable or resilient stop carried by the standard for preventing the latch or top weight from flying off when thrown quickly upward.

15 A further object of the invention is to provide a latch having an opening through one of its walls through which opening the spring or resilient stop member projects. This opening also performs two other functions which are: first, it reduces the weight 20 of the latch; and second, by means of this opening the latch having a rearwardly engaging extension may be cast without coring, thereby reducing the cost of the casting to the minimum.

25 30 With these and other objects in view, the invention consists of certain novel features of construction, as will be more fully described, and particularly pointed out in the appended claims.

35 In the accompanying drawings:

Figure 1—is a side elevation partly in section showing my improved construction of carrier with the spool in position thereon.

Fig. 2—is a front elevation of the latch.

40 Fig. 3—is a rear view of the latch.

Fig. 4—is a sectional side elevation of the latch.

Fig. 5—is an end view of the latch.

Fig. 6—is a perspective view of the stop 45 spring which is attached to one of the faces of the standard.

In the operation of the ordinary carrier an unusual pull on the yarn causes a quick upward throw of the tension weight and 50 also of the latch, which sometimes permits the spool to rotate several teeth before the latch can again drop to catch it, and this excessive unwinding action of the spool often causes the yarn to snarl and sometimes 55 allows the tension weight to drop sufficiently to engage the machine stopping mechanism.

To obviate this difficulty, I have provided a standard 10 on the frame 11 and have formed a groove 12 on the inner face thereof adjacent the top of the spool 13 and in this recess I have mounted an elongated spring finger 14 secured at its upper end by the rivet 15. The lower end of this spring is provided with an outwardly extending hump or projection 16 with its end 17 turned 60 sharply inwardly into the deeper portion of the recess 18 in the standard. 65

Slidably mounted on this improved form of standard is a latch member 19 having a pawl 20 adapted to engage the ratchet teeth 70 21 in the head of the spool 13. The body portion of this latch is provided with an inner wall 22 adapted to set adjacent the spool, which wall is cut out at 23 forming an opening therethrough and providing an 75 upper cross bar from which the pawl 20 projects. This cut out portion also forms a lower cross bar 25. The rear edges 26 of this latch are provided with narrow fingers 27 projecting inwardly or toward each 80 other, which fingers reach around back of the standard to hold the latch in position thereon.

A feature of this construction of latch is that these fingers 27 on the back of the latch 85 are directly opposite the opening 23 in the front of the latch, which construction enables the latch to be drawn from the sand in casting without the necessity of coring, thereby considerably reducing the expense 90 of providing these latches by a casting operation.

Another feature of this construction of latch is that the hump of the spring stop finger 16 normally extends through this 95 opening 23 in the latch during the operation of the carrier.

The advantages of my improved construction of latch and standard are, first, the latch may be readily positioned on the 100 standard by passing it down over the spring stop until the protuberance on this spring enters the space 18 in the latch, the end 17 of this spring being turned inward abruptly so that when any unusual upthrow of the 105 latch occurs the edge of the lower cross bar 25 will engage this yieldable stop and prevent the latch from being raised too high above the ratchet teeth on the spool.

Another feature of this construction is 110 that this resilient stop causes the latch to at once rebound and catch the next adjacent

tooth of the spool thereby preventing excessive unwinding of the yarn therefrom.

When it is desired to remove the latch from the standard it is only necessary to 5 press the spring stop inward, which will permit the latch to readily pass thereover.

I have illustrated one means whereby my 10 invention may be carried out, but I do not wish to limit myself to the specific construction shown as various changes in shape and form of the several features may be necessary. I, therefore, desire it to be understood that I reserve the privilege of resorting to 15 all the mechanical changes to which the device is susceptible, the invention being defined by the appended claims.

I claim:

1. A carrier for braiding machines comprising a frame having a spindle carrying 20 a ratchet toothed spool, a standard on said frame having a yieldable stop member secured to one of its faces, and a latch slidably mounted on said standard and adapted to engage said stop only when raised above 25 the release position to limit an excessive upward throw.

2. A carrier for braiding machines comprising a frame having a spindle carrying a ratchet toothed spool, a standard on said 30 frame having a yieldable stop member secured to one of its faces, and a latch slid-

ably mounted on said standard and provided with an opening in one of its walls through which said stop projects to engage and limit the upward throw of said latch.

3. A carrier for braiding machines comprising a frame carrying a toothed spool, a standard on said frame provided with a recess in one of its faces near its upper end, a latch slidably mounted on said standard, 40 a spring catch attached to said standard and provided with a hump adapted to be depressed into said recess to permit said latch to slide thereover on said standard, the underside of said spring being also provided 45 with a shoulder to engage the latch and limit its upward throw.

4. A carrier for braiding machines comprising a frame carrying a toothed spool, a standard on said frame provided with a recess in one of its faces near its upper end, a latch slidably mounted on said standard, the free end of the spring being bent to form a hump, said hump being adapted to be depressed into said recess to permit said latch 50 to slide thereover on said standard, said free end of the spring being bent abruptly inward to provide a shoulder to engage and limit the upward throw of the latch.

In testimony whereof I affix my signature. 60

EDWARD S. JUDKINS.
